CUFF LINK

William S. McMenemy, Stamford, Conn., assignor to Countess Mara, Incorporated, New York, N.Y., a corporation of New York

Filed July 10, 1961, Ser. No. 65,856

Term of patent 7 years

(Cl. D17—7)

Fig. 1.

Fig. 2.

Fig. 3.

Fig. 4.

FIG. 1 is a front elevational view of a cuff link showing my new design;

FIG. 2 is a right side elevational view thereof;

FIG. 3 is a top plan view thereof; and

FIG. 4 is a rear elevational view thereof.

I claim:

The ornamental design for a cuff link, substantially as shown.
